UNITED STATES PATENT OFFICE.

MYRON L. HANEY, OF BELOIT, WISCONSIN.

DEVICE FOR OPENING AND CLOSING GARAGE-DOORS AND THE LIKE.

1,395,240.

Specification of Letters Patent.

Patented Oct. 25, 1921.

Application filed February 10, 1920. Serial No. 357,546.

To all whom it may concern:

Be it known that I, MYRON L. HANEY, a citizen of the United States, residing at Beloit, in the county of Rock and State of

5 Wisconsin, have invented certain new and useful Improvements in Devices for Opening and Closing Garage-Doors and the like, of which the following is a specification.

This invention pertains in general to devices for opening and closing doors, and has more particular reference to fluid operated mechanisms adapted particularly for opening garage doors or any swinging doors.

The primary object of the present invention is to provide a simple and improved mechanism operated preferably by fluid pressure for quickly opening a pair of hinged doors, especially of the kind used in the entrance way of a garage. It should be understood however, that my improvements are in no way limited to this particular use as they are generally applicable for opening any swinging doors.

Another object of my invention is to provide a novel mechanism operating in conjunction with a door-check and closer on each door, whereby the doors will be opened by pressure applied through my improvements and will be closed by the action of 30 said door closers.

Still another object resides in the provision of a novel control device, a simple actuation of which, as by pulling a cord, will cause the doors to be opened and held open 35 until the cord or operating member of the control device is again actuated for causing the doors to be closed.

My invention also contemplates the provision of mechanism which may be applied 40 as an attachment to any pair of swinging doors equipped with a door check and closer of conventional design.

Other objects and attendant advantages 45 relative to various features of the invention and not heretofore mentioned will be better appreciated as the invention becomes better understood by reference to the following description when considered in connection with the accompanying drawings, in which—

50 Figure 1 is a front elevation of a pair of garage doors equipped with an opening and closing device embodying my improvements;

Fig. 2 an enlarged plan view of the parts directly associated with the left hand door 55 and showing in dotted lines the doors swung partly open;

Fig. 3 an enlarged section view taken on the line 3—3 of Fig. 1; and

Fig. 4 a detailed sectional view taken on the line 4—4 of Fig. 3.

In the present illustration of my improvements I have taken a typical example of the doors at the entrance to a garage. It will be observed in Fig. 1 that the doors 5 and 6 are hung at their outer edges on the hinges 7 in a conventional manner and that these doors are adapted to swing inwardly upon said hinges. Inasmuch as the entrances of this kind are of relatively large dimensions, the doors are quite heavy and it is difficult for one person to open both doors at one time.

It is desired under the circumstances of this particular use to open both doors quickly and with little effort on the part of the operator and to hold the doors open for such period as is necessary. This I propose to do by simply actuating a control device as by pulling a cord once for the purpose of opening the doors and a second time for causing them to close. I have further proposed to utilize the ordinary door check and closer very generally employed on doors of this kind for the purpose of closing them after they have been opened. In the present instance each door is equipped with a door check and closer 8 of conventional design, and inasmuch as these devices are of well known construction, I have deemed it unnecessary to illustrate them other than in outline. These devices generally include an oscillatory part connected with a stationary part of the door casing or the adjoining framework. In the present instance I equip this oscillatory part with a segmental gear 9 and also an arm 10 which is pivotally connected by means of an extensible link 11 to the door casing 12. The segmental gear 9 meshes with a rack 13 which is connected to a piston operable in a cylinder 15 fixedly mounted on the door. The piston is adapted to be actuated by fluid such as air under pressure conveyed through means of a pipe 16 which extends to the hinged edge of the door and is connected thereto through means of a flexible hose section 17 with a pipe connection 18 that leads to the supply port 19 Fig. 3 in a casing 20. This casing is preferably attached centrally above the doors and connects in the manner just described to the cylinder 15 on each door. It will be seen from Fig. 1 that the door 6 is

100

110

equipped with mechanism similar in every respect to the parts just described as being applied to the door 5. From the foregoing construction it will be manifest that when 5 air is applied under pressure to both the pipes 18, the racks 13 will be forced outwardly, thereby oscillating the segmental gears 9 and causing the doors to be swung inwardly on the hinges 7. In other words, 10 viewing Fig. 2, the segmental gear 9 will be oscillated in a counter-clockwise direction, thereby imposing a thrust on the joined parts 10 and 11 and forcing the door 5 open, that is, to swing in a clockwise direction.

15 I have now provided a device for controlling the admission of air under pressure to the pipes 18. This control will admit air under pressure to the cylinders 15 and then release the air. In the present instance this 20 control device consists of a casing 20 mentioned above, in which is mounted a pair of oscillatory valves 21 and 22 having diametrical ports 23 and 24 respectively, adapted to register with the vertical passageway 25 25 through the casing. Air is admitted under pressure to the upper end of the passage 25 from any suitable source. In the position of the valves shown in Fig. 3 port 23 is closed and port 24 is open to the outer atmosphere, 30 this being the position with the doors closed. The ports 23 and 24 spaced at right angles to each other are connected in permanent relation by means of spur gears 26 and 27. Thus by revolving one of these gears 90° the 35 position of the valves will be changed to close one and open the other and upon a similar actuation of the gears through the next 90° the valves will be opened and closed in inverse order, and upon each successive 40 90° movement of the gears the position of the valves will be changed. For so actuating the valves I have equipped gear 26 with a ratchet wheel 28 having four equally spaced notches 29 therein. A lever 30 45 loosely mounted concentric with the valve 21 carries a spring pressed pawl 31 constantly urged against the periphery of the ratchet wheel 28. This lever is equipped at its outer end with a weight 37 and connected to 50 a rod 32 which is guided in a bracket 33 for vertical movement. The stops 34 and 35 on the rod 32 regulate the up and down movements of this rod. By means of a cable 36, attached to the upper end of the rod and 55 guided over pulleys (not shown) to any suitable point within the reach of an operator, the rod 32 may be raised at will. Upon raising the rod 32 to its upper extremity limited by the stop 35 the ratchet wheel 28 will be moved 60 90° in a clockwise direction viewing Fig. 4. This operation will turn the valves 21 and 22 through a similar number of degrees, causing the port 23 to register with the passage 25 and closing the port 24. The result of 65 this operation is that the air under pressure

from the supply tank will be admitted to both of the cylinders 15, causing both doors to be swung inwardly to open positions. Any suitable means may be provided for cushioning the doors when they have been 70 opened. The doors remain in this open position as long as the air pressure is applied to the pistons. When the cable 36 is released, the weight 37 returns the lever 30 to its starting position and engages the pawl 75 31 in the next succeeding notch 29 in the ratchet wheel. The valves are held against accidental displacement by means of springs 38, which likewise hold the valves seated. The stop 34 on the rod 32 limits the downward movement of the lever, to the proper extent so that upon the next actuation of the cable 36, the lever 30 will turn the valves through another 90°, thereby closing port 80 23 and opening the port 24, as shown in Fig. 85 3. This permits the air confined in the cylinders 15 to escape through the lower outlet of the passage 25 and allows the doors to be closed under the influence of the closing device 8. It will thus be seen that in order 90 to open or close the doors it is only necessary to actuate the cable 26 in a simple pulling movement, and that when the doors have been opened they will remain so until the next actuation of the cable.

95 My improvements may be applied to practically any door or set of doors, although they are especially adapted for opening comparatively heavy doors as in the case of garage doors or those closing large passageways. My improvements are also of special utility in connection with garage doors because being operated by fluid pressure, no special air tank and pump is required as most garages are equipped with this apparatus used for tire filling purposes. It is believed that the foregoing conveys a clear understanding of the principles and objects of my invention and while I have illustrated and described but a single working embodiment it should be understood that various changes might be made in the construction and arrangement without departing from the spirit and scope of the invention as expressed in the appended claims, in which— 105 110 115

I claim:

1. In a door-check and closer device, the combination of a hinged door, a door-check and closer carried by the door and having an operating part, a connection between said 120 operating part and a fixed support, whereby the door upon being opened will be closed and checked by said device, a fluid pressure device supported by the door, a connection between said fluid-pressure device and the operating part of the door-check and closer device, and means for causing said fluid-pressure device to open the door through the agency of said operating part of the door-check and closer device. 125 130

2. The combination of a hinged door, a door-closing device fixed to said door and having an operating part connected with a stationary support, and a fluid-pressure device supported on the door and having a part connected with said operating part of the door-closer device and adapted to be operated by fluid pressure for opening the door.
3. The combination of a hinged door, a door-closing device mounted upon the door adjacent to its hinged end and having an operating part connected with a fixed support, a cylinder fixed to the door beyond said closing device, a piston for the cylinder, a connection between the piston and said operating part of the door-closing device, and a fluid-pressure supply and control connected with the cylinder for operating the piston by fluid pressure for opening the door.
4. The combination with a hinged door and a door-check and closer therefor, including an oscillatory member, of a cylinder and a piston therefor carried by the door, a rack attached to the piston, a gear fixed to the oscillatory member and meshing with said rack, a connection between the oscillatory member and a stationary part for opening the door when said member is oscillated, and means for admitting fluid under pressure to said cylinder for actuating the piston and thereby opening the door.
5. The combination of a hinged door, a device mounted on the door for closing the same, said device having an oscillatory operating part equipped with a segmental rack, a connection between the segmental rack and a stationary part through means of which the door opening and closing movements are transmitted, a fluid-pressure device mounted on the door, and a rack meshing with said segmental gear and adapted to be operated by said fluid-pressure device for opening the door.
6. The combination of a hinged door, a device mounted on the door for closing the same, said device having an oscillatory operating part equipped with a segmental rack, a connection between the segmental rack and a stationary part through means of which the door opening and closing movements are transmitted, a fluid-pressure device mounted on the door, a rack meshing with said segmental gear and adapted to be operated by said fluid-pressure device for opening the door, and a fluid-pressure control means so constructed that upon initial actuation the fluid-pressure device will be operated to open the door and hold it in opened position, and upon subsequent actuation said pressure will be released allowing the closing device to close the door.

MYRON L. HANEY.
